CHARLES M. FAIRBANKS AND JOSEPH B. McCUNE, OF HARTFORD, CONN.,
ASSIGNORS TO ELIAS A. WILKINSON, OF NEWARK, N. J.

NEEDLE-CLAMP AND THREAD-GUIDE FOR SEWING-MACHINES.

SPECIFICATION forming part of Letters Patent No. 268,652, dated December 5, 1882.

Application filed June 19, 1882. (No model.)

To all whom it may concern:

Be it known that we, CHARLES M. FAIRBANKS and JOSEPH B. McCUNE, of the city and county of Hartford, and State of Connecticut, have invented certain new and useful Improvements in Needle-Clamps and Thread-Guides for Sewing-Machines, described in this specification and the drawings thereof.

The invention consists in improvements relating to the needle-clamp on the needle-bar for controlling the thread.

Figure 1 is a perspective view of one form of the invention. Fig. 2 is a horizontal section of the same. Fig. 3 is a detail view thereof.

In the form of construction shown the needle-clamp A is held to the needle-bar C by a nut, B. The face of the needle-clamp has a vertical thread-groove, a. The needle-clamp is held from turning by a screw, D, having a smooth point, m, to enter a hole, g, in the needle-bar. This screw also serves to hold the thread guide E in proper relation to the face of the needle-clamp. The thread guide may be bent to conform to the thread-groove, and made of spring metal. The thread is drawn under the end of the thread-guide into the thread-groove, and then supported by the thread-guide, which, when made of spring metal, closes after the thread is in position and holds it in place.

Before our invention needle clamps had been made with thread-guides and devices to hold them in position and prevent them from turning; but our improvement differs materially therefrom in having a spring thread-guide held to the needle-clamp without the assistance of other devices by a screw having a smooth point to enter a hole in the needle-bar to prevent the needle-clamp from turning when the nut is loosened to remove or replace the needle, thus avoiding the necessity of adjust-

ing the needle-clamp thereafter, and the consequent oiling of the fingers of the operator and the necessary delay.

The details of construction may be varied within the scope of the improvements. For example, the spring thread-guide may be reversed in position from that shown in the drawings, and, instead of a groove, g, in the needle-clamp, a bend may be made in the spring thread-guide.

We claim as our invention—

1. The combination, in sewing mechanism, of needle-bar C, having hole g, needle-clamp A, having groove a and nut B, screw D, having smooth point m, and spring thread-guide E, held to the needle-clamp by the screw D alone, the smooth point of which prevents the clamp from turning, substantially as set forth.

2. The combination, in sewing mechanism, of a needle-clamp held to a needle-bar by a nut, a spring thread-guide held to the needle-clamp wholly by a screw having a smooth point entering a hole in the needle-bar to prevent the needle-clamp from turning when the nut is loosened to remove or replace a needle, substantially as set forth.

3. The combination of a needle-clamp, a needle-bar, and a thread-guide, the thread-guide held to the needle-clamp wholly by a screw having a smooth point entering the needle-bar to prevent the clamp from turning when it is loosened, substantially as set forth.

In testimony whereof we hereunto subscribe our signatures, in the presence of two attesting witnesses, on the 31st day of May, 1882.

CHARLES M. FAIRBANKS.
JOSEPH B. McCUNE.
